UNITED STATES PATENT OFFICE.

FRANK R. PETTITT, OF SPOKANE, WASHINGTON.

INTERNAL-COMBUSTION ENGINE.

1,276,262.

Specification of Letters Patent. Patented Aug. 20, 1918.

Application filed August 13, 1917. Serial No. 186,075.

To all whom it may concern:

Be it known that I, FRANK R. PETTITT, a citizen of the United States, residing at Spokane, in the county of Spokane and 5 State of Washington, have invented certain new and useful Improvements in Internal-Combustion Engines, of which the following is a specification.

The present invention relates to improvements in internal combustion engines, and 10 is designed especially for the purpose of utilizing the vapor which is generated in the crank case of the engine due to the combustion in the cylinders of the engine.

15 Usually this vapor is expended in radiated heat through the crank case, but by my invention I propose to transfer the vapor from the crank case and introduce it into the cylinder of the engine as a part of the 20 fuel charge. The vapor generated in the crank case is found to be impregnated with vaporized oil, and the oil thus carried to the cylinder as a part of the fuel charge serves, as a lubricant for the piston in the 25 cylinder.

The invention consists in certain novel combinations and arrangements of parts for accomplishing the above purpose, as will be hereinafter pointed out and claimed.

30 In the accompanying drawings I have illustrated one complete example of the physical embodiment of my invention constructed and arranged according to the best mode I have so far devised for the practical 35 application of the principles of my invention.

Figure 1 is a side elevation of an internal combustion engine equipped with my invention.

40 Fig. 2 is a top plan view of Fig. 1.

Fig. 3 is a transverse sectional view of the engine.

Fig. 4 is an enlarged detail view of the breather pipe of the engine.

45 Fig. 5 is a side view of the cap for the breather or oil lubricating inlet for the engine.

Fig. 6 is a top plan view of the cap.

Fig. 7 is a view of a joint in the pipe leading from the breather, showing in dotted lines a valve for turning the vapor toward either the manifold of the engine or the carburetor.

50 Fig. 8 is an enlarged view of a perforated plate inserted in the top of the crank case.

Fig. 9 is a sectional view of this plate of Fig. 8.

In the preferred embodiment of my invention as shown in the drawings, I have illustrated an internal combustion engine of 60 usual type in which the crank case is indicated by the numeral 1, the clutch case is indicated by the numeral 2, and the usual manifold 3 and well-known type of carburetor 4.

In Fig. 1 I have shown a pipe 5 connected to the crank case and opening therein at 6, and this pipe passes upwardly over the engine and is connected to the carburetor at 7. This pipe 5 is designed to transfer 70 the vapor generated in the crank case, from the crank case to the carburetor, and as this vapor is highly charged with oil in suspension, it will readily be seen that the oil in the vapor will be carried into the cylinder 75 and may there be utilized to lubricate the piston. The vapor is introduced with the fuel charge in the top of the cylinder, and in this manner the cylinder is lubricated from the top as well as from the bottom in 80 the usual splash system.

In order to create a circulation of air in the crank case, I employ a perforated plate 8 in the top plate 9 of the clutch case, which communicates with the crank case. The 85 plate 8 has perforations 10 through which the air may be filtered to the clutch case and passed from thence into the crank case, and the passage of air is automatically controlled by a disk or valve 11 which is regulated by a spring or resilient arm 12 attached to the plate. The valve is closed under normal conditions, but when the vapor is carried away from the crank case, atmospheric pressure opens the valve against 95 the spring lever, and permits entrance of air into the crank case.

If desired, a second pipe, as 13, may be utilized, and in Figs. 1 and 2 it will be seen that this pipe is attached to the breather 100 pipe 14, which is the lubricating oil inlet for the engine, and the pipe 13 extends from the breather toward the rear of the engine, where it has a joint 15 provided with a valve 16, which is controlled by a lever arm 105 17, and this valve is designed to pass the vapor to the carburetor 4, by means of the pipe 18, or to the manifold 3 through the pipe 19. The breather is equipped with a threaded cap 20, and the cap has a perfo- 110

- rated top 21 which is regulated by a damper, or perforated disk 22 in manner similar to a stove damper. The introduction of air through the cap is controlled by this damper, 5 and the air through the perforated cap may be cut off when it is desired to direct the vapor into the engine. When the vapor is not being used, the cap may be removed entirely.
- 10 From the above description it will be evident that I have provided a system of piping for use in connection with an internal combustion engine by means of which the purposes above set forth are accomplished.

What I claim is:

In an internal combustion engine, the combination with a portion of the crank case having an opening, a carbureter, and the cylinder communicating with the carbureter, of a pipe connecting the crank case and carbureter, a perforated plate in the crank case opening and a valve therefor, and a resilient arm controlling the valve whereby a circulation of vapor is automatically maintained as described.

In testimony whereof I affix my signature.

FRANK R. PETTITT.
